UNITED STATES PATENT OFFICE

BENJAMIN A. MORTON, OF NEW YORK, N. Y.

WINDOW STRUCTURE

Application filed September 7, 1929. Serial No. 390,915.

This invention relates to improvements in window constructions and has for its object to provide a novel form of window which is adapted for houses, railway cars, and other structures.

The primary object of my invention is to provide a window wherein the several sashes or panes of the window may be operated from a single handle or other operating member, and wherein any number of sashes or panes may be employed in the window, all of the panes being shifted by the single operating member into the vertical space of one of the sashes or the whole group of sashes may be shifted into a recess in the frame, thereby providing a window opening co-extensive with the area of the window frame.

A further object of the invention is to provide an operating mechanism for adjusting the several sash sections which is entirely concealed within the window frame and occupies but little if any more space than ordinarily allowed between the actual window casing and the adjacent parts of the building structure.

A further object of the invention is to provide a clamping member for the several sashes which will be not only burglar-proof, but weather-proof when the window is fully closed, and which will hold all the sashes, whether closed or partly open, securely against rattling or displacement.

Other objects of the invention will appear from the following specification wherein I have described a preferred embodiment of the invention.

In the accompanying drawings, wherein my improved window is illustrated,

Fig. 1 shows the window in elevation with part of the casing cut away to better show the operating mechanism;

Fig. 2 is a vertical sectional view on line 2-2 of Fig. 1;

Fig. 3 is a vertical section on an enlarged scale on line 3-3 of Figs. 1 and 4;

Fig. 4 is a sectional detail on line 4-4 of Fig. 3;

Fig. 5 is an enlarged section on line 5-5 of Fig. 2;

Fig. 6 is a sectional detail on line 6-6 of Fig. 5;

Figs. 7 and 8 are detail views illustrating a modification; and

Fig. 9 is a detail view of a modified form of apparatus in which the sash sections are lowered into a compartment beneath the window sill.

Referring to the drawings, 1 indicates the vertical side members of the window frame, 2 the window sill and 3 the top member of the frame. The window frame illustrated is wider than the actual window opening, in order to provide spaces 4 within which the counterweights 5 of the several movable sashes (here shown as three in number) may operate. The three movable sashes, 6^a, 6^b, 6^c, respectively, lie one above the other and are guided in a single guide groove 7 formed in the vertical window casing member 8 which forms a side wall of the window opening. Back of the groove 7 and within the compartment 4 of the counterweights is a vertical bar 9 having a groove 10 aligned with the guide groove 7 but of greater width, as shown in Fig. 5.

Each of the several window sashes is provided on its side edges with projections 11 somewhat thinner than the material of the sash itself, which projections pass through the guide groove 7 into the enlarged groove 10 of the bar 9. The lower horizontal edges of the sashes are grooved as shown in Fig. 2, to fit over a corresponding projection on the upper horizontal edges of the adjacent sashes, so that when the sashes are closed down one on top of the other a weather-tight joint will be formed. In the structure shown in the drawing the sashes are of metal and the meeting edges are accurately shaped to fit. The sashes may, however, be made of wood, in which case the meeting edges should be faced with rubber to produce a weather-tight joint. Also, the window sashes may be dispensed with entirely, in which case the meeting edges of the glass pane should be ground to fit.

Attached to each sash at a point above the middle horizontal line along the outer edge of the rib or projection 11 is a plate 12 carrying a pivot pin 13 on which a hook-shaped

member 14 is loosely mounted by means of a slot 14^a. The purpose of this member will be later described.

Attached to each member 14 is a chain 15 which carries at its outer end the counterweight 5. These chains are trained over sprocket wheels 16 supported in the window frame above the top of the casing, the several sprocket wheels being offset slightly with respect to each other so that the several chains will not interfere. The counterweights 5 for the lower sash hang down directly from the outer peripheries of the respective sprocket wheels, whereas the weights for the middle 15 and upper sash sections, respectively, are trained over idlers 17 so positioned that the weights will hang clear of each other. The two sprocket wheels for each sash section are connected together to rotate in unison by 20 means of transverse shafts 18 so that when the sprocket chains on one side of the window frame are rotated by the window-operating mechanism, the sashes will be lifted evenly on both sides.

25 The window-operating mechanism comprises an operating handle 19 supported on the end of a hollow shaft 20 mounted for rotation and axial movement in bearings 21 in the window frame near the bottom at one side, as shown in Figs. 1 and 2. The construction of the operating shaft and its attached parts is shown in enlarged detail in Fig. 6. Supported on the shaft 20 between the two bearings are three sprocket wheels 35 22^a, 22^b, 22^c, corresponding to the several sash sections. The inner periphery of each of these sprockets is toothed as indicated in Fig. 6, providing in effect a series of keyways adapted to receive the projecting tooth of a movable 40 key 23 supported within the hollow shaft 20 and pressed normally outward by a spring 24. Also supported on the hollow shaft 20 between the two bearings is a gear or pinion 25 whose inner periphery is likewise grooved 45 to receive the end of the pivoted key 23. The several sprockets and the gear are separated by washers to facilitate their independent rotation and also to insure the proper positioning of the key for engagement with but one 50 gear or sprocket wheel. The tooth 27 on the movable key 23 is pointed, as shown in Fig. 6, at an angle such that when the hollow shaft is shifted axially in or out in the bearings 21, the key will be forced back into the hollow 55 shaft as the pointed tooth passes under the washers 26, the spring pressing the key upwardly as soon as the apex of the tooth passes the ring.

The shifts 28^a, 28^b, 28^c which carry the 60 sprockets 16 for the counterweight chains, are of different lengths, as indicated in Fig. 2, and each carries on its end a sprocket wheel 29^a, 29^b, 29^c, respectively, overlying the correspondingly lettered sprocket wheels on the 65 hollow shaft 20. Continuous sprocket chains

70 connect the respective pairs of sprocket wheels whereby the longitudinal or axial movement of the hollow shaft 20 will serve to clutch one of the sprocket wheels 22 to the hollow shaft, and upon subsequent rotation of the hollow shaft the selected sash will be correspondingly raised or lowered.

In order that the several sash sections will 75 occupy no more window area when the windows are open than a single sash section, I provide means at the top of the window for shifting the sash sections out of line with each other as they reach the top of the frame. With three movable sections as illustrated, this may be accomplished by shifting the first section toward the front of the window, the second section toward the rear of the window, and allowing the third section to remain 80 in position between the other two and in line with the groove 7. It is for the purpose of so shifting the sash sections that the hooked members 14 are provided. The two upper sash sections are provided with these members with their hooks oppositely placed, as 85 shown in Fig. 2, in order that the two sash sections may be shifted one to the front and one to the rear, leaving a space between for the third sash section to which the sprocket chains may be directly connected.

90 In Figs. 3 and 4 I have illustrated the mode 95 of operation of the top sash section. The hooked members 14 are slotted for the passage of the pivoted pins 13. In the normal position of these members, that is, the position in which the sash sections are entirely in 100 their closed position, the ends of the members having the hooks 31 extend upwardly, whereas the opposite end to which the sprocket chains 15 are attached lie below the pivots. The parts 14 are prevented from 105 rotating during the up and down movement of the sash sections by the sides of the grooves 10, these grooves being just wide enough to permit the free passage of the members 14 and the plates 12 on which they are pivoted.

110 The hooked members are also held against tilting during the movement of the sashes by a groove 32 back of the groove 10 in line with the guide groove 7, which groove serves 115 to guide the pins 33 to which the sprocket chains are attached. When the sash section passes above the top member of the window casing it is shifted toward the front of the window by means of the continued upward pull on the chain 5 on the members 14. That 120 is to say, in operating the mechanism to raise the sashes the operator has only to continue the rotation of the handle 19 a partial turn beyond the distance necessary to elevate the sash and this continued movement serves to 125 shift the sash section out of line with the guide groove to permit the next sash section to be raised into its proper place. The mechanism to accomplish this consists primarily of guides 34 supported in the window frame 130

above the top horizontal member of the window casing. This top casing member is slotted to permit passage of the sash sections and when the sash clears the top of the casing its edge guide 7 is clear of the groove 8 and the further movements of the sashes controlled by the members 14.

Above the window casing the recess in the face of the vertical bar 9 is enlarged as shown, and the guides 34 are attached to the opposite front edges of the bar 9 practically overlying the recess. Each guide consists of a metal plate of a thickness to engage the pivoted members 14 and the pin 33. At their lower ends the edges of the two guides are extended at the back to provide ribs 34^a for guiding the pins 33, while at the front the edges of the guides are spaced apart a sufficient distance to engage the opposite side edges of the members 14 and prevent them from turning until the lower edges of the sash sections clear the top of the window casing. About the middle of their length the guides 34 are cut away so that the edges of the guides flare outwardly from each other to permit the hooked members 14 to turn on their pivoted pins as they pass into the wider space.

It will be understood, of course, that the pin 33 is offset somewhat with respect to the slot 14^a so that the sprocket chain lies slightly to the rear of the pin 13, hence when the flared portion of the guides is reached the pull on the sprocket chain will tend to turn the hooked member of the upper sash, as viewed in Fig. 3, in a counterclockwise direction to the extent permitted by distance between the guides.

The members 14 at each end of the sash are operated in unison by reason of the transverse shafts and beveled gears at the top of the window frame, and when these members are permitted by the widening distance between the guides 34 to turn beyond the horizontal, the sash sections will be shifted to the front as far as permitted by the pin-and-slot connection between the members 14 and the sash section, as shown in full lines in Fig. 3. At this point the guides 34 are provided with recesses 35 so shaped that when the members 14 reach this position the hooks 31 will extend into the recesses and thus prevent further turning movement of the members 14 under the pull of the sprocket chains.

The lateral movement permitted by the pin-and-slot connection is sufficient to shift the sash section clear of the slot in the window casing to permit the second sash section to be elevated to a position behind the first sash section. To operate the second sash section the operating handle 19 is shifted outwardly a sufficient distance to bring the point of the key 23 beyond the ring 26 lying between the sprocket 22^a and the sprocket 22^b, so that the key will be pressed outwardly

into one of the grooves of the inner periphery of the sprocket 22^b. In this position the rotation of the handle will turn the sprockets 22^b, 29^b, and the corresponding beveled gears and transverse shafts to rotate the sprocket wheels for the corresponding counterweights, in unison. As stated above, the hook-shaped members 14 for the sash section 6^b are the same as those provided for the top sash section except that the hooks are oppositely faced and the pin 33 is offset to the rear of the slot 14^a instead of to the front, whereby when the hooked sections are free to turn as the members 14 pass into the widened space between the guide members 34, they will turn in a clockwise direction instead of in a counterclockwise direction, as will be obvious.

The members 14 are pivoted to the ends of the sash section 6^b a somewhat greater distance from the upper edge of the sash section than are the pins 13 of section 22^a, also the notches 35 of the rear guide 34 are located below the notches in the front guide, so that the members 14 of the sash section 6^b will turn to shift the section to the rear without interference with the members 14 of the section 6^a, as indicated in dot-and-dash lines in Fig. 3.

The purpose of the hooks 31 is to insure the return of the sash sections to a position over the vertical guide grooves, and also to insure a return of the members 14 to their normal position. When the chains which lift the windows are drawn to their uppermost position, as shown in Fig. 3, the hooks 31 will be projected into the notches 35 in the guides 34. Now, when the operating shaft is turned in the opposite direction to lower the sash, the hooks will serve as pivots for the outer ends of the members 14, thereby causing the latter to turn under the weight of the sash and when the members 14 pass the horizontal position the pins on the sash sections will slide to the opposite ends of the grooves in the members 14, thereby restoring the sash to its position over the guide grooves. As the sash continues to descend the members 14 will continue to turn until they are almost restored to vertical position, at which point the hooks will clear the notches in the edges of the guides and allow the sash to descend freely to its closed position or to whatever other position it is adjusted by the operation of the handle 19.

The operating handle is also utilized for clamping the sash sections against movement when the window is closed, or in any desired partially open position. This clamping mechanism is operated by means of the gear 25 carried by the shaft 20. I have shown two modifications of the window-operating mechanism, the preferred form being shown in Figs. 1-5 inclusive. As here shown, the gear 25 meshes with a short rack section 40

carried by a vertical bar 41 mounted for vertical movement on the inner face of the vertical window frame members 9. The bar 41 is supported by means of inclined slots 42 on pins 43 projecting from the adjacent face 5 of the frame member 9, so that when the bar is elevated by the rotation of the gear 25 and the rack section 40, it will be shifted toward the left, as shown in Figs. 3, 4 and 5, to thereby clamp against the projecting edges 11 of the sash members.

Obviously, also, when the operating shaft 19 is turned in the opposite direction, the bar 41 will be shifted away from the sash sections, thereby releasing them for operation. 13 The clamping bar 41 serves not only to clamp the sash sections by reason of the force exerted through the operating handle, but if it be attempted to raise the sash section without 20 operating the handle to shift the bar clear of the edges 9, the bar will be pressed more tightly against the sash sections by reason of the wedging action of the inclined slots on the pins 43.

25 If the ceiling height above the window frame is sufficient, the sash sections may be shifted entirely out of the window opening, but in order to provide as much illumination as possible, the space above the actual window frame is preferably closed on the outside 30 by means of a hinged sash 54 of the same size as the movable sash sections. This sash section is hinged at the top to swing outwardly and in case of rain, when the other sash sections are in closed position, may be partially 35 opened to provide ventilation.

In the modification of the clamping mechanism shown in Figs. 7 and 8, the gear 25 is utilized to actuate a rack bar 46 which is 40 mounted for vertical movement only in the same position as the bar 41. The rack bar 46 is provided with several rack sections 48 which cooperate with the pinions 49 supported on pins 50, which in turn are mounted for 45 rotation in stationary bearings 51 attached to the vertical frame member 9 adjacent the several sash sections. The pins 50 are threaded as shown in Fig. 7, and carried by the threads are nuts 52 which are also supported 50 in the bearings 51 for longitudinal movement therein. The nuts are welded or otherwise secured to an angle bar 53 whose edge extends into the groove 10 adjacent the ribs 11 of the sash sections so that when the pinions 49 are 55 rotated by the movement of the rack bar 46, the bar 53 will clamp the sashes against movement.

60 In Fig. 9 I have shown an arrangement wherein the sash sections are lowered into a compartment 60 below the window sill. This mechanism is the same as that employed in the first described construction except that the hook 14^a is of modified construction so as 65 to shift the sash out of line with the guide

groove 10 on the downward movement of the sash instead of the upward movement.

The hook 14^a is attached to the sash sections by means of a pin 13^a working in a slot in the hook as before but the chain 15 is attached to the hook by a pin 33^a at the middle of the hook instead of at the end so that the point of the hook will be raised on sidewise movement of the sash, instead of lowered.

70 During the movement of the sash in the guide groove the point of the hook extends downwardly and the pin 13^a lies at the inner end of its slot immediately over the pin 33^a so that, except when the pins have an exact "dead center" relation to each other the weight of the sash tends to turn the hook about the pin 33^a as a center. A very light spring 61 may be provided to initiate the tilting movement but this is not necessary. At the proper point below the sill the side walls 85 34^b of the channel in which the hooks are guided are shaped to permit the hooks to turn so as to shift the bottom sash 6^a to the right as shown in Fig. 9, and the middle sash to the left so that the third sash may drop between them. In turning, the pointed ends of the hooks are projected into recesses 62 in the walls 34^b so that when the sashes are raised the hooks will be turned in the reverse direction.

90 It will of course be understood that the mechanism may be variously modified without departing from the spirit of the invention. Electric motors might readily be provided for operating the window sections, in which case the motors could be mounted in the space above the windows and controlled by push buttons arranged at any point alongside the window frame. Also, of course, the number of sash sections may be greater or less. No change in the mechanism will be required in order to provide a greater number of sash sections, other than the necessary duplication of the counterweights, sprocket chains and sprocket wheels. The same mechanism may be used for shifting any number of sash sections out of line with the guide grooves by simply making the parts of the proper dimensions to insure a lateral shift of sufficient amplitude.

105 110 115 The window is thoroughly weather-proof. The several sash sections fit closely together and as the clamping bar 41 extends the entire height of the window and firmly clamps the edges of the sashes against the outside portion of the window casing, there is no possibility of rain or wind entering. The window is of pleasing appearance and readily adapts itself to different pane designs. Also, unmounted sheets of plate glass may be used, giving a virtually unbroken light opening when the window is closed as well as when open.

120 125 I claim:

1. In a window structure the combination 130

of a plurality of sashes mounted for vertical movement, means for shifting one of said sashes transversely out of the path of its vertical movement, and an actuating mechanism for effecting both movements of said sash.

2. In a window structure the combination of a plurality of sashes mounted for vertical movement, means for shifting one of said sashes transversely out of the path of its vertical movement, an actuating mechanism for effecting both movements of said sash, said actuating member comprising a rotary operating member and means whereby continued rotation of said member successively effects both said movements.

3. In a window structure the combination of a plurality of sashes mounted for vertical movement, means for shifting a plurality of sashes transversely out of the path of their vertical movement, mechanism for moving said sashes in the manner described, and a common operating member for said sashes.

4. In a window structure the combination of a plurality of sashes mounted for vertical movement, means for shifting a plurality of sashes transversely out of the path of their vertical movement, mechanism for moving said sashes in the manner described, and a common operating member for said sashes, said member comprising manually adjustable means for selecting the sash to be operated thereby.

5. In a window the combination of a plurality of sashes vertically movable in the same plane into and out of the window opening, and means for simultaneously clamping all the sashes in said window opening against movement.

40 6. In a window the combination of a plurality of sashes vertically movable in the same plane into and out of the window opening, and means for simultaneously clamping all the sashes in said window opening against movement in any position of adjustment therein.

7. In a window a plurality of sashes supported for rectilinear movement in the same plane, means for adjusting certain of said sashes in opposite directions out of said plane, and means for adjusting a third sash into position between the first-mentioned sashes.

55 8. In a window, a plurality of sashes vertically adjustable in the same plane, a common operating member for adjusting said sashes, a clamping device for simultaneously clamping a plurality of sashes against movement, said clamping device being actuated by said common operating member.

60 9. In testimony whereof I affix my signature.
BENJAMIN A. MORTON.
